VESSEL

Robert E. Hauert, 910 Prospect, Elmhurst, Ill., and Fritz H. Pahlow, 344 Orchard Ave., Hillside, Ill.
Filed Sept. 10, 1963, Ser. No. 367,892
7 Claims. (Cl. 215—1)

This invention relates to a vessel and more particularly to an improved construction for a transparent bottle which includes a pocket for mounting within the pocket a label or other identifying indicia, which label is protected by the material of the bottle.

It is appreciated that in many instances labels are particularly important on containers. In particular, a label on a container, such as, a prescription bottle is important in that it normally indicates the patient for whom the prescribed compound is intended, the prescribing physician, the compounding pharmacist, as well as the number of the prescription in the records of the compounding pharmacist. In many instances, when prescription bottles are put into use, medicines or other liquids often run down the face of the bottle, thereby defacing the label. This defacement often obliterates a prescription number. A situation of this nature causes severe problems when it is necessary to refill the prescription, because it is difficult, if not impossible, to find a prescription without its number. It is, therefore, a principal object of the present invention to provide a bottle which contains a label receiving pocket, which pocket may be sealed closed to prevent the label from being defaced either by a liquid or by accidental removal of the label.

It is another object of the herein disclosed invention to provide a vessel construction which allows a label to be easily and quickly applied to the vessel.

It is a further object of this invention to provide a vessel construction in which a label is protected by the material of the vessel, and which label is clearly visible when applied to the vessel.

It is a still further object of the instant invention to provide a vessel construction which has a container and a transparent wall formed integral with the container forming a pocket for receiving a label and a seal closing said pocket to prevent a liquid from entering the pocket.

Other objects and uses of the herein disclosed invention will become readily apparent to those skilled in the art upon a perusal of the following specification in light of the accompanying drawings in which:

FIGURE 1 is a side elevation of a vessel embodying the herein disclosed invention;

FIGURE 2 is a partial cross-sectional view of the vessel shown in FIGURE 1 showing the interior construction of the vessel;

FIGURE 3 is a cross-sectional view taken on line 3—3 of FIGURE 1;

FIGURE 4 is an enlarged fragmentary cross-sectional view of a portion of FIGURE 3 showing a seal in position for sealing the upper portion of a pocket;

FIGURE 5 is a partial cross-sectional view of a vessel similar to the vessel shown in FIGURE 1, but showing a pocket having an opening in its bottom;

FIGURE 6 is a cross-sectional view taken on line 6—6 of FIGURE 5;

FIGURE 7 is an enlarged fragmentary cross-sectional view of a portion of FIGURE 5 showing a seal in position closing the bottom of the pocket of the vessel;

FIGURE 8 is a side elevation of a vessel embodying the herein disclosed invention showing a seal in a partially applied attitude;

FIGURE 9 is a cross-sectional view taken on line 9—9 of FIGURE 8;

2

FIGURE 10 is an enlarged fragmentary cross-sectional view taken on line 10—10 of FIGURE 8;

FIGURE 11 is a cross-sectional view of a generally cylindrical vessel embodying the herein disclosed invention;

FIGURE 12 is a cross-sectional view taken on line 12—12 of FIGURE 11;

FIGURE 13 is an enlarged fragmentary cross-sectional view of a portion of the vessel shown in FIGURE 11 showing the cap of the vessel in a partially raised position and a down or locked position for the cap being shown in dotted form.

Referring now, to the drawings and especially FIGURES 1 through 4, a transparent glass bottle generally indicated by numeral 10 is shown therein. The bottle 10 includes a container having a bottom 12 with a continuous upwardly extending side wall 14 formed integral with the bottom. The side wall has a neck 16 formed integral with the upper portion of the side wall, which neck contains an integral thread 18 for receiving and holding a cap. A recess 19 is formed in a portion of the side wall. A transparent face wall 20 has opposite longitudinal side edges formed integral with the side wall and the lower edge of the face wall is, also, formed integral with the side wall. The face wall covers the recess 19 and blends into the side wall, but the face wall is spaced from the side wall to form a pocket 22 between the face wall and the side wall. As is evident from the FIGURES 1 and 2, the pocket 22 has an opening at the top to allow labels or other indicia to be positioned in the pocket.

A seal is provided to close the pocket 22. A continuous first bead 24 is formed integral with the side wall 14 which bead is spaced slightly from the upper edge of the face wall 20. A second bead 26 is, also, formed integral with a portion of the side wall and is formed integral with the top of the face wall 20. Positioned between the beads 24 and 26 is an O-ring 28. As may be clearly seen in enlarged FIGURE 4, the O-ring is held in between the beads 24 and 26 to seal closed the top of the pocket 22. It may be appreciated that the O-ring 28 in its natural position is smaller than the outside periphery of the vessel. The O-ring is made of rubber in this instance, though any other suitable resilient material may be used. Thus, when the O-ring is placed between the beads 24 and 26, the resilience of the O-ring holds the O-ring into tight engagement with the beads, thereby holding the O-ring in position and forming a seal between the beads to seal closed the pocket 22.

In normal usage, the vessel is filled, and a label 30 is then placed in the pocket 22 by sliding it down between the side wall 14 and the face wall 20. The O-ring 28 is then placed into position between beads 24 and 26 to seal closed the top of the pocket. It may be appreciated that should any liquid, such as, medicine contained in the vessel be allowed to drip down the neck 16, the liquid will flow down and flow over the O-ring 28 but will not enter the pocket 22. Thereby, the label 30 is protected from defacement by any liquid which may flow down the neck 16 by gravity. It may further be appreciated that the label 30 is clearly visible in view of the fact that face wall 20 is made of a transparent material. The face wall 20, also, protects the label from being pulled off accidentally or by wearing off by continuous handling of the vessel.

Looking, now, to FIGURES 5 through 7, a transparent glass bottle generally indicated by the numeral 50 is shown therein. The bottle or vessel 50 includes a container which has a bottom 52 and a continuous side wall 54. The side wall has a recess 55 formed in one side. A neck 56 is formed integral with the upper portion of the side wall 54, and the neck contains a thread 58 for holding a bottle cap thereon.

The vessel 50 includes a transparent face wall 60 which has a pair of opposite side edges and an upper edge formed integral with and blending into the side wall. The face wall covers the recess 55 so that there is a pocket 62 formed between the transparent face wall 60 and the side wall 54, which pocket provides a protective receptacle for a label. A lower bead 64 is formed integral with the side wall 54 and is continuous on the periphery of said side wall. Said bead 64 is positioned below and spaced slightly from the bottom edge of the transparent face wall 60. A second continuous bead 66 is formed integral with the bottom edge of the transparent face wall 60 and a portion of the side wall 54. The bead 66 is spaced from bead 64 to provide adequate space for receiving a seal therebetween. A rubber O-ring 68 is mounted between the two beads. As in the case of O-ring 28, the normal size of O-ring 68 is less than the distance on the periphery of the container side wall 54, so that the resilience of the O-ring holds the O-ring between the beads 64 and 66. The resilience of the O-ring holds the O-ring in sealing engagement with the beads so that the bottom of pocket 62 is sealed closed.

It may be appreciated that a label such as label 30 may be inserted in the pocket 62. The O-ring 68 is then applied to keep the label from sliding out of the bottom of the pocket. In the event that a liquid is spilled, the liquid flows down the neck 56 and on to the face wall 60. The label in the pocket is protected by the face wall 60. It may be further appreciated that in the event that the liquid should flow down to the bottom of the face wall and on to the O-ring 68, the label is still protected in the event that the vessel should be inverted which would tend to cause the liquid to flow in the opposite direction. As was pointed out above, the O-ring 68 forms a seal between the beads 64 and 66 so that liquid has no opportunity for entering the pocket 62, and thereby damage the label contained in the pocket.

Looking, now, to FIGURES 8, 9 and 10, a transparent glass bottle or vessel, generally indicated by numeral 100, is shown therein. The vessel 100 includes a container which has a bottom 102 and a continuous upstanding side wall 104 formed integral with the bottom. As in the case of vessels 10 and 50, the vessel 100 has a neck 108 which is formed integral with the uppermost edge of the side wall 104. The neck 108 includes a thread 110 for holding a cap on the vessel. A recess 109 is formed in the side wall 104. Formed integral with the side wall 104 and covering the recess 109 is a transparent face wall 111 which blends into side wall 104. The face wall 111 has two portions, i.e., an upper transparent face wall 112 which has its upper edge and side edges formed integral with the side wall and a lower transparent face wall 114 which has its bottom edge and side edges formed integral with the face wall 104. The lower face wall 114 is spaced slightly from the upper face wall 112, thereby providing a slot 116 between the upper and lower face walls. The upper face wall has a bevelled edge 118 in its lower portion. The lower face wall has as its upper edge a bevelled edge 120 so that the slot 116 is a generally upwardly sloping slot. Each of the face walls, that is, the upper and lower face walls 112 and 114 have a seal recess 122 and 124, respectively, formed therein. A seal 126 is mounted in these seal recesses to close the slot 116.

It may be appreciated that a label, such as, label 128 may be slipped into a pocket 130 which is formed by the side wall and the face walls by sliding the label upward in through slot 116 generally as shown in FIGURE 9. Once the label is in the pocket, it drops down into the attitude shown in FIGURE 10, that is, with its lower edge at the bottom of the pocket. The label is thus securely in the pocket and may not be readily removed. A seal 126 which is in this instance a transparent adhesive tape is positioned in the recesses 122 and 124 to seal closed the slot 116. It is, thus, apparent that should any liquid flow down the face wall 112, it would be pre-

vented from entering the slot 116 by the seal 126. The label is protected by the transparent face wall and the seal.

Referring, now, to FIGURES 11, 12 and 13, a glass bottle or vessel generally indicated by numeral 200 is shown therein. The vessel 200 includes a glass container having a bottom 202 and a continuous upstanding side wall 204 formed integral with the bottom. The side wall has a recess 205 formed therein and a transparent face wall 206 is connected to the side wall which covers the recess. The face wall has its side edges formed integral with the side wall as well as its bottom edge to form a label receiving pocket 208 and to blend into the side wall.

In order to provide a seal for the pocket, a bead 210 is formed integral with the uppermost edge of the face wall 206 and a portion of the side wall 204. A rubber O-ring 212 is positioned in sealing engagement with the upper edge of the face wall 206 and in sealing engagement with the side wall 204. The diameter of O-ring 212 is less than the outside peripheral distance of side wall 204 so that the resilience of the O-ring keeps it in tight engagement with the side wall and face wall 206.

A cap 214 is mounted on the uppermost end of the container to seal closed the container. The cap, which is an integral resilient cap, includes a sealing annulus 216. The sealing annulus 216 engages the O-ring 212 to hold the O-ring in tight engagement with the face wall 206. The cap 214, also, has a locking annulus 218 which resiliently engages the bead 210 to hold the cap in position, and thus hold the seal 212 in position.

A label is positioned in the pocket 202, and the O-ring 212 is then placed over the opening of the pocket. Inasmuch as the normal size of the O-ring is slightly less than the periphery of the side wall 204, the resilience of the O-ring holds the O-ring in tight engagement with the wall 204. The cap 214 is applied by placing the cap 214 over the open end of the container, and the sealing annulus 216 is placed into position in engagement with the O-ring 212. As the cap is forced down, the locking annulus 218 is forced outward to go around the bead 210. Once the force is released, the cap is locked into position by virtue of the resilience of the locking annulus 218 and the interference of the locking annulus with bead 210. The sealing annulus 216 tends to force the O-ring 212 into tight engagement between the side wall 204 and the upper edge of the face wall 206. It may be appreciated that in order to remove the contents from the instant vessel, it is necessary to remove the cap 214. The resilience of the O-ring keeps the O-ring 212 in sealing engagement with the side wall and the end of the face wall. Thus, a label in the pocket 208 has no opportunity of getting out of the pocket. Furthermore, should there be spilling out of the contents of the container, the O-ring 212 provides the necessary seal to prevent a liquid from entering the pocket 208. The exclusion of the liquid protects the label. It is, also, apparent that the label is protected from wear by face wall 206.

Although specific embodiments of the herein disclosed invention have been shown and described herein, it is readily apparent that other materials may be substituted for glass, rubber and other materials without departing from the spirit and scope of the present invention. It is to be further understood that various modifications and changes in the construction of the vessel shown and described herein may be readily made by those skilled in the art without departing from the spirit and scope of this invention. It is to be expressly understood that the instant invention is limited only by the appended claims.

What is claimed is:

1. A transparent vessel including, a container having a bottom and a continuous upstanding side wall formed integral with said bottom, a transparent face wall hav-

ing opposite sides and a bottom formed integral with the side wall forming a label receiving pocket between the face wall and a side wall, a label positioned in the label receiving pocket, a first bead formed integral with the side wall and being spaced from the upper edge of the face wall, a second continuous bead formed integral with the side wall and with the upper edge of the face wall and being spaced from the first bead, and a continuous ring seal mounted between said beads sealing the space between the upper edge of the face wall and the side wall to close said pocket.

2. A transparent vessel including, a container having a bottom and a continuous upstanding side wall formed integral with said bottom, said side wall having a recess contained therein, a transparent face wall having opposite sides and a bottom edge formed integral with the side wall and covering said recess to form a label receiving pocket between the face wall and the side wall, a label positioned in the label receiving pocket, a neck portion formed integral with the upper edge of the upstanding side wall, said neck portion having a cap holding means, a first continuous bead formed integral with the side wall and being spaced from the upper edge of the face wall, a second continuous bead formed integral with the upper edge of the face wall and a portion of the side wall and being spaced from the first bead, and a continuous ring seal mounted between said beads sealing the space between the upper edge of the face wall and the side wall to close said pocket.

3. A transparent vessel including, a container having a bottom and a continuous upstanding side wall formed integral with said bottom, a transparent face wall having opposite edges fixed to the side wall forming a label receiving pocket between the face wall and a side wall, said pocket having an aperture in the lower portion thereof to provide an entrance for positioning a label in said pocket, a label positioned in the label receiving pocket, and means for holding the label in said pocket.

4. A transparent vessel including, a container having a bottom and a continuous upstanding side wall formed integral with said bottom, a transparent face wall formed integral with the side wall forming a label receiving pocket between the face wall and a side wall, a label positioned in the label receiving pocket, a bead formed integral with the side wall and being positioned below the face wall, and a continuous seal mounted in engagement with the bead and engaging the face wall for closing the bottom of the pocket to retain the label in said pocket.

5. A transparent vessel including, a container having a bottom and a continuous upstanding side wall formed integral with said bottom, a transparent face wall having side edges and a top edge formed integral with

5
10

the side wall forming a label receiving pocket between the face wall and the side wall, a label positioned in the label receiving pocket, a continuous first bead formed integral with the side wall and positioned below the bottom of the transparent face wall, a second continuous bead formed integral with the bottom edge of the transparent face wall and a portion of the side wall, and a continuous seal mounted between the beads in sealing engagement with the bottom edge of the transparent face wall to close the bottom of the pocket.

15
20

6. A transparent vessel including, a container having a bottom and a continuous upstanding side wall formed integral with said bottom, said side wall having a recess formed therein, a transparent face wall having side edges and a top edge fixed to the side wall covering said recess to form a label receiving pocket between the face wall and the side wall, a label positioned in the label receiving pocket, a neck portion formed integral with the upper edge of the side wall, said neck portion having a cap holding portion for mounting a cap thereon, a continuous first bead formed integral with the side wall and positioned below the bottom of the transparent face wall, a second continuous bead formed integral with the bottom edge of the transparent face wall and a portion of the side wall, and a resilient ring seal mounted between the beads in sealing engagement with the bottom edge of the transparent face wall and the side wall to close the bottom of the pocket.

25
30

7. A transparent vessel including, a container having a bottom and a continuous upstanding side wall formed integral with said bottom, a transparent face wall having opposite edges and its bottom edge formed integral with the side wall forming a label receiving pocket between the face wall and the side wall, a label positioned in the label receiving pocket, a bead formed integral with the uppermost edge of the transparent face wall, a continuous seal positioned in engagement with the upper edge of the transparent face wall and the side wall of the container, and a cap for closing the container having a sealing annulus in engagement with the seal to hold the seal in position to close the upper portion of the pocket and a locking annulus in engagement with the bead to hold the cap on to said container.
